UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

CAR-HEATING SYSTEM.

1,369,276.

Specification of Letters Patent.

Patented Feb. 22, 1921.

Application filed January 31, 1919. Serial No. 274,298.

To all whom it may concern:

Be it known that I, EDWARD E. GOLD, a citizen of the United States of America, residing in the borough of Manhattan, city, 5 county, and State of New York, have invented certain new and useful Improvements in Car-Heating Systems, of which the following is a specification.

This invention relates to car heating systems of the type in which the heating medium consists of high or low pressure steam, and the present purpose is to provide for adequately heating a number of different sections or compartments in a car, and for 10 regulating the degree of heat in each compartment without necessarily affecting any of the remaining compartments, and without disturbing the main heating supply.

The above-mentioned purpose may be carried out, in general, by providing a common supply extending through the several sections or compartments, and arranging in each compartment a separate radiator unit connected with the common supply at one 25 end. The opposite end of the radiator unit in each compartment is open to the atmosphere, so that the water of condensation can be constantly discharged, instead of having to pass back to the common supply and into 30 the system as a whole. The temperature of each compartment can be controlled at will, independently of the remaining compartments, by a separate cut-off provided for each radiator unit, and preferably accessible 35 within the compartment. Thus, when it is desired to furnish additional heat to any section, the corresponding control is opened and a portion of steam from the main supply pipe passes through the radiator unit 40 and thence to the atmosphere in the form of condensation.

A further and important feature of my improvement resides in providing a simplified and economical construction, which will 45 permit connection to be made between the common supply pipe and each radiator unit and also to exhaust from said radiator unit to the atmosphere. This I accomplish in an efficient and entirely practical manner, 50 and without the necessity of any complicated valve arrangement or other delicately operating parts. To these and other ends, the invention consists in certain other improvements and details of parts, as will be 55 hereinafter more fully described, the essen-

tial features of the invention being pointed out in the claims following the specification.

In the drawings,—

Figure 1 is a perspective view, showing the application of one embodiment of the invention to a compartment car, the walls of the latter being broken away to disclose the interior arrangement;

Fig. 2 is a perspective view of a preferred form of coupling, which I intend to utilize in connection with the system;

Fig. 3 is a top plan view of the coupling shown in Fig. 2;

Fig. 4 is an end elevation of the same;

Fig. 5 is a sectional view on line 5—5 of Fig. 4, and

Fig. 6 is a sectional view on line 6—6 of Fig. 3.

In the embodiment illustrated in Fig. 1, A designates the usual train pipe extending 75 lengthwise under the floor of the car and furnishing the heating medium, which is carried thence upwardly into the car to be distributed through various independent sections or compartments, such as designated 80 by *a*, *b* and *c*, respectively.

Steam is conducted from the train pipe A through branch pipes *d* and *e* to the steam supply pipe *f*, the return end of which is designated by *h*, which leads to the usual thermostatic controlling member *i*, which may be any usual vapor-valve. From the branch pipe *d* a second branch *e'* also leads to a supply pipe *f'*, the return end of which is designated by *h'* and also leads to the thermostatic controlling member *i*. An additional branch pipe *j* leads from the train pipe A to a supply pipe *k*, the return end of which is designated by *l* and leads to the thermostatic controlling member *m*.

While I have shown and described three supply pipes, namely, *f*, *f'* and *k*, they are not all essential to the purpose of the invention, as the fundamental principle of my improvement contemplates the use of one supply pipe, such as *f*, leading through and connecting with a series of sections or compartments. In modern car construction, however, it is somewhat undesirable from an engineering standpoint to supply all of 105 the compartments in a car from a single pipe, owing to the great distance over which it is necessary to extend the pipes, and for this reason, I prefer to utilize two or three supply pipes, connecting them with 110

the train pipe and leading them to different parts of the car. For a clear understanding of my present invention, it is only necessary to consider one of these supply pipes, and with this in view, the following description will relate to the supply pipe *f*.

The supply pipe *f* extends through the sections or compartments *b* and *c*, as well as several similar compartments which do not appear in the drawings, and in each of such compartments there is provided a separate and independent radiator unit, each connected with the supply pipe *f* in such a manner as to receive the heating medium, when desired, and to discharge it to the atmosphere. The radiator unit for compartment *b* is designated by *B*, and that for compartment *c* is designated by *C*. The arrangement of the radiator unit in each compartment, and its manner of connection with the common supply pipe is the same in every instance and, for convenience, I will confine the description to one of these, namely, the radiator *B*.

It is highly desirable to have a simple and inexpensive coupling or connecting means to accomplish the desired coöperation between the supply pipe and the radiator unit, and I accomplish this preferably by means of the coupling shown in Figs. 2 to 6, inclusive, and designated generally by *D*. This coupling consists preferably of an integral, or one-piece structure, and includes an inlet portion *n*, and an outlet portion *o*, the inlet and outlet portions being separated by a wall *p*. The inlet portion *n* is provided with connections *q* at its opposite ends, for connection with the corresponding opposite portions of the supply pipe *f*, as shown in Fig. 1. Thus, the inlet portion of the coupling *D* forms, in effect, a part of the supply pipe *f*, so that the heating medium can pass continuously therethrough. The inlet portion *n* also has an additional connection *r*, preferably extending upwardly, as shown in Figs. 1 and 2, and adapted to be joined to the inlet end of the radiator unit *B*. Arranged within said inlet end of the radiator unit is a cut-off consisting of any suitable form of valve, as designated by *s*, and preferably controlled from within the section or compartment by a handle *t* adapted to move the controlling valve through a rotatable rod *u*, and a connecting link *v* which is joined to the arms fixed upon the rod *u* and the valve member respectively. When the valve *s* is closed, the heating medium cannot pass beyond it, and consequently the radiator unit *B* remains unheated, while at the same time steam is free to pass through the coupling *D* and the supply pipe *f*, and thereby to heat any of the remaining radiator units whose valves may be open.

When the valve *s* is opened, a sufficient amount of steam is diverted from the supply

pipe *f* and passes into the radiator unit *B*. The opposite end of the radiator unit *B* leads to a connection *w* in the outlet portion of the coupling. From this point, the steam passes through the outlet portion into the 70 downwardly extending connection *x*. The latter is provided with a barrier *y* having a relatively small opening or jet orifice *z* therein, which is of sufficient size only to assure the draining off of the condensation as it 75 accumulates in the radiator unit. *E* designates an outlet or drip pipe which is preferably joined to the connection *x*, and extends downwardly to a point beneath the floor of the car and carries off to the atmosphere 80 the condensation after it has drained through the opening *z*.

By the use of a coupling of this character, the incoming steam maintains the wall *p* and the outlet portion always in a more or 85 less heated state and thus prevents the likelihood of the condensation freezing in cold weather. Moreover, the coupling is of a form that permits it to be manufactured rather cheaply, and also makes it possible 90 to establish the necessary connection between a supply pipe and a radiator unit very easily. The coupling is independent 95 of the controlling valve, and there are, therefore, no parts which can become disorganized or affect the main supply in the pipe *f*. The barrier *y* maintains sufficient pressure within the radiator unit *B*, and by connecting the latter with the atmosphere so as to constantly discharge the condensation, the supply pipe can be tapped for as 100 many radiators as desired, and all of the radiator units fed from one common supply will be assured of steam under proper conditions, such as would not be the case if the 105 condensation from the first radiator unit were permitted to return to the common supply pipe and intermingle with the steam entering subsequent radiator units.

While I have shown and described a preferred form of coupling, the invention is not to be limited in scope to this particular arrangement, since the same purpose can be accomplished in other ways, without departing from the underlying novelty of the invention which consists in providing each compartment of a car with an independent radiator unit, which may be connected at will with a common supply and exhausts to the atmosphere. The invention in its further aspect comprehends any form of coupling member by which steam may be fed from a common supply to a radiator unit, while the condensation from the latter may be in turn carried off and discharged into 120 the atmosphere through the same coupling 125 which connects with the supply.

The construction herein described is well adapted to low pressure heating systems, and particularly to the atmospheric pressure 130

or so-called vapor system. Heretofore in such systems the drip from branch radiators has been carried through a common return pipe to the thermostatic element of an inlet 5 or vapor-valve, which has certain disadvantages. With the present construction the vapor-valve is controlled by the discharge from the main radiator f or f' , (or both, if both be in service) and the branch radiators 10 B, C, etc., discharge to the outer air directly. The steam lost with the discharge of condensation through the drip orifices is negligible because of the slow outflow, due to the very low pressure used.

15 What I claim is:—

1. The combination with a car of a heating system including a train-pipe, radiating pipes open to the atmosphere, including a radiating supply pipe extending longitudinally within the car, a thermostatic inlet valve admitting steam from said train-pipe to said radiating supply pipe, the discharge from said pipe communicating with said thermostatic valve to control the same, and 20 separate radiating units branching from said radiating supply pipe, each controlled by a separate inlet valve and each discharging beneath the car independently of such thermostatic inlet valve, so that the latter is not 25 heated by the discharge from such units.

30 2. A car heating system according to claim 1, with a contraction in the outlet from each such separate radiating unit.

35 3. In a railway car divided into separate sections or compartments, the heating system of claim 1, the branch radiating units thereof each located in a separate compartment, whereby each compartment is heated partly by radiation from the radiating supply pipe common to several compartments, and partly by such radiating unit confined 40 to such compartment, the latter being separately controllable at will by its own inlet valve.

45 4. A car heating system according to claim 1, each branch radiating unit having its inlet from the radiating supply pipe and its outlet for condensation closely adjoining, so that such outlet may be continuously heated from 50 such inlet.

5. A structure according to claim 1, char-

acterized by a coupling member having an inlet portion connecting with said radiating supply pipe and a connection leading to said radiator unit, and an outlet portion having 55 a connection with said radiator unit and a passage open to the atmosphere.

6. A structure according to claim 1, characterized by an integral coupling member having an inlet portion connecting with said radiating supply pipe and a connection leading to said radiator unit, an outlet portion having connection with said radiator unit and also a passage open to the atmosphere, 60 a wall separating said inlet and outlet portions of the coupling, and a closure in said last-named passage having a relatively small opening to permit discharge of condensation.

7. A structure according to claim 1, characterized by an integral coupling having an inlet portion, a connection from such inlet portion leading to said supply pipe, a connecting extending upwardly from said inlet portion toward said radiator unit, an outlet 70 75 portion having a connection at one end with said radiator unit, and an outlet extending downwardly and leading to the atmosphere.

8. A structure according to claim 1, characterized by an integral coupling having an 80 inlet portion, a connection from such inlet portion leading to said supply pipe, a connection extending upwardly from said inlet portion toward said radiator unit, an outlet 85 portion having a connection at one end with said radiator unit, an outlet extending downwardly and leading to the atmosphere, and a closure in said outlet portion having a relatively small opening to permit discharge of condensation.

9. A structure according to claim 1, characterized by a coupling connecting with said supply pipe, and also with the inlet end of the radiator unit, the opposite end of the radiator unit leading to a passage in said 95 coupling and thence to the atmosphere.

In witness whereof, I have hereunto signed my name.

EDWARD E. GOLD.
